(57) **CLAIM**

The ornamental design for an exterior patch for a shoe as shown and described.

DESCRIPTION

FIG. 1 is a perspective view of an exterior patch for a right shoe showing my new design.

FIG. 2 is a top plan view thereof.

FIG. 3 is a left side elevation view thereof.

FIG. 4 is a cross-sectional view thereof taken along line 4-4 in FIG. 3.

FIG. 5 is a front elevation view thereof.

FIG. 6 is a rear elevation view thereof.

FIG. 7 is a perspective view of an exterior patch for a left shoe showing my new design.

FIG. 8 is a top plan view thereof.

FIG. 9 is a right side elevation view thereof.

FIG. 10 is a cross-sectional view thereof taken along line 10-10 in FIG. 9.

FIG. 11 is a rear elevation view thereof; and,

FIG. 12 is a front elevation view thereof.

In FIGS. 1-12, the dashed broken lines illustrate a shoe or portion thereof as environmental structure and form no part of the claimed design.

1 Claim, 4 Drawing Sheets
